S. M. BEERY.

RESILIENT TIRE FILLING.

APPLICATION FILED AUG. 20, 1913.

1,106,769.

Patented Aug. 11, 1914.

UNITED STATES PATENT OFFICE.

SAMUEL M. BEERY, OF INDIANAPOLIS, INDIANA.

RESILIENT TIRE-FILLING.

1,106,769.

Specification of Letters Patent. Patented Aug. 11, 1914.

Application filed August 20, 1913. Serial No. 785,623.

To all whom it may concern:

Be it known that I, SAMUEL M. BEERY, a citizen of the United States, residing at Indianapolis, in the county of Marion and State of Indiana, have invented a new and useful Improvement in Resilient Tire-Fillings, of which the following is a specification.

My invention relates to an improvement 10 in the construction of the resilient filling to be confined about the rim by the outer casing of an automobile-tire.

The object of my invention is to provide a tire-filling of the kind referred to, which 15 shall be simple and durable and shall effectively serve to resiliently cushion the load like the inner inflated tube of a pneumatic tire, but, unlike the latter, without liability to be injuriously affected by puncturing.

20 In the accompanying drawings, Figure 1 is a view in broken sectional elevation of a section of my improved resilient tire-filling; Fig. 2 is an enlarged view in cross-section of the filling confined in an outer casing, and 25 Fig. 3 is a broken and partly sectional view of the annular filling looking at the inner periphery thereof.

To build the annular filling, in embodying my invention in the best form now 30 known to me, I use a central core 4, for which a hempen rope is desirable, and sheath the core in a resilient tube 5, preferably of rubber-hose variety. A spiral spring 6 surrounds the tube 5 and is, in turn, enveloped 35 in a sheath 7 of suitable fabric, such as canvas, which should be tacked, by one or more lines of strong stitches, as represented at 8, to each convolution of the spring to hold it against creeping or buckling thereon. About the canvas sheath is wrapped a 40 longitudinally-split resilient tube 9, of the same material as the tube 5, and the edges are fastened together either by cementing them, or by means of lacing them together, 45 as shown at 10, through eyelets 10' (Fig. 3) provided at intervals along the edges. The respective ends of the elements thus far described are suitably fastened together to reduce the whole to annular form. About the

tube 9 is wrapped spirally a strip of thick, 50 highly-flexible cushioning material 11, preferably felted wool, though other material for the purpose may be used without departure from my invention. The whole is then wrapped in an outer layer 12 of strong 55 fabric, preferably canvas, which is fastened in place at its edges, as by a lace 13 passed through eyelets 14 therein (Fig. 3). The annular body thus formed is designed to be mounted on a suitable sectional clencher-^{rim} 60 (not shown) of an automobile-wheel and held thereon by an outer rubber-and-canvas casing 15 of usual or any suitable construction adapting it to be secured in place by the rim. I have devised a construction of sec- 65 tional rim especially for securing an outer-casing 15 over my present improved filling-body. It is not illustrated herein, however, but forms the subject of my separate application for Letters Patent filed concurrently 70 herewith on the 20th day of August 1913, Serial Number 785,622. The body thus formed when used on an automobile-wheel renders the latter easy-riding, being resilient 75 in a high degree and effectively cushioning the load in passing over obstructions, besides being comparatively light and desirable.

What I claim as new and desire to secure by Letters Patent is—

An article of manufacture adapted to be 80 used as a filler for tires, comprising a central solid core, having an irregular cross section, a resilient casing tightly fitting the outer surface of said core, the irregularities forming air spaces therebetween, a spiral spring 85 85 the convolutions of which are spaced apart to provide a second series of air spaces wound about said casing, a second resilient casing closely fitting about said spring, and a strip of light, flexible cushioning material 90 wound about said casing, all of said parts being in relatively close contact with one another, thereby to produce a compact resilient tire filler having concentric air spaces.

SAMUEL M. BEERY.

In presence of—

L. HOLZHALL,
O. C. AVISUS.
